TERMINAL BUSHING FOR ELECTRICAL CONDUITS

Lawrence M. Curtiss, Mountainside, N.J., assignor to The Thomas & Betts Co., Elizabeth, N.J., a corporation of New Jersey

Application June 26, 1958, Serial No. 51,564

Term of patent 14 years

(Cl. D26—5)

Fig. 1.

Fig. 2.

Fig. 3.

Fig. 4.

Fig. 5.

Fig. 1 is a view in perspective of a conduit bushing showing my new design;

Fig. 2 is a front end view in elevation;

Fig. 3 is a side view in elevation;

Fig. 4 is a rear end view in elevation; and

Fig. 5 is a vertical sectional view of the conduit bushing taken on the line 5—5 of Fig. 2.

I claim:

The ornamental design for a terminal bushing for electrical conduits, as shown and described.
